UNITED STATES PATENT OFFICE.

THOMAS H. CHUBB, OF POST MILLS, VERMONT.

DESIGN FOR A FISHING-REEL.

SPECIFICATION forming part of Design No. 13,921, dated May 22, 1883.

Application filed April 21, 1883. Term of patent 14 years.

To all whom it may concern:

Be it known that I, THOMAS H. CHUBB, of Post Mills, in the county of Orange and State of Vermont, have invented a new and Improved Design for Fishing-Reels, of which the following is a full, clear, and exact description.

Reference is to be had to the accompanying drawings, forming part of this specification, in which Figure 1 is a perspective view of my newly-designed fishing-reel; and Fig. 2 is a front elevation of the same, these two views being deemed necessary to fully illustrate my design.

Heretofore fishing-reels have been made with plane sides to their frames and with plane flanges to their spools.

The leading features of my design are the raised or convexed ends of the frame, surrounded by a plane border, and the radially-corrugated flaring flanges of the spool.

A is the reel-frame, the middle parts, B, of

the ends of which are raised or convexed, and the outer parts or borders, C, are plane. The spool D has its flanges E flared and radially corrugated.

This design gives the reel a neat, attractive, and ornamental appearance.

Having thus described my invention, I claim as new and desire to secure by Letters Patent—

1. The design for a fishing-reel herein shown and described, the same consisting of the ends of the reel-frame, having the middle part, B, raised or convexed and surrounded by a plane border, C.

2. The design for a fishing-reel herein shown and described, the same consisting of the flanges E of the spool, made flaring and having radial corrugations.

THOMAS HENRY CHUBB.
